ABRASIVE PAD FOR GRINDING LENSES

Waldemar Stoppacher, White Plains, N.Y., assignor to
Interoptic Laboratories, Inc., Elmsford, N.Y.

Filed Dec. 10, 1973, Ser. No. 423,174

Term of patent 14 years

Int. Cl. D8—05

U.S. Cl. D8—90

FIG. 1

FIG. 2

FIG. 3

FIG. 1 is a perspective view of an abrasive pad for grinding lenses showing my new design.

FIG. 2 is a right side view thereof; and

FIG. 3 is a bottom plan view thereof.

I claim:

The ornamental design for an abrasive pad for grinding lenses, as shown and described.
